ABSTRACT OF THE DISCLOSURE

A support for the internal frame of a bed to lend the head portion of the frame lateral reciprocating motion. Such portion is hung on pivoted vertical arms, and drawn from side to side by a power unit under the head end of the bed. The power unit has a worm drive with a side link connected to the head portion of the internal frame. At the foot end of the bed the frame rests on a central ball-joint built in the base of the bedstead. With the device designed for inducing relaxation and sleep, the reciprocating movement by vertical suspension is not necessary at the foot end of the bed, and the device is therefore adaptable to beds having a low board or no board at the foot end.

My invention relates to beds, and more particularly to means for imparting a movement to the same similar to that employed in Pat. No. 2,617,122 to L. A. Chisholm, dated Nov. 11, 1952, for a cradle. In this patent the cradle is suspended at its ends from parallel straps pivoted at the top to end-boards of the cradle-supporting structure. This makes it possible to swing the cradle from side to side with a motion more gentle than a rocking one and conducive to relaxation and sleep.

One object of the present invention is to retain the suspension and movement of the frame within the bedstead in a manner similar to the cradle in the above mentioned patent, but adapt the movement to beds which have a low board or no board at the foot end by reducing the support of the internal frame in that region to a simple pivot for purposes of simplicity and to omit the reciprocating movement where it is not needed.

A further object is to provide a ball-joint and bracing assembly for the internal frame at the foot end of the bedstead which eases the reciprocating movement of the frame and insures the stability of the latter.

Another object is to provide a power source for imparting the reciprocating movement which is compact and confined to the head end of the bedstead.

A better understanding of the invention may be gained by reference to the accompanying drawing, in which:

FIG. 1 is a front elevation of the improved bed, partly in section;

FIG. 2 is a side view looking from right-to-left at FIG. 1;

FIG. 3 is a section on the line 3—3 of FIG. 2 with portions broken away; and

FIG. 4 is a fragmentary section on the line 4—4 of FIG. 3 with portions broken away.

Referring specifically to the drawing, 10 denotes the base of a bedstead suitable for the present purpose, the head board of the bedstead being indicated at 11. The internal bed frame is shown at 12, and may contain slats or other supports (not shown) for a box spring or mattress.

Supporting means for the bed frame at the foot of the bed are shown in FIGS. 1 and 2. Thus, a center post 15 is mounted on the base 10 and reduced to a screw 15a which depends freely through the base to receive a washer 16 and securing nut 17. The post rises through the bottom 18a of a brace 18 extending crosswise under the foot end of the frame 12, the end portions of the brace being se-

2

cured to the frame by bolts 20. The upper end of the post 15 receives a ball 21 which seats in a socket 12a secured in the frame. The construction just described constitutes the post 15 as support for the foot end of the frame about which the latter and its brace 18 may rotate in lateral directions. The brace 18 bolted at 20 and received on center post 15 will prevent inner frame or support 12 from having relative longitudinal or transverse movement with respect to base 10. The ball 21 received in socket 12a will permit restrained pivotal movement about post 15; and the inner frame 12 rests on ball 21 to permit the pivotal movement.

The head board 11 of the bedstead has corner posts 11a; and these are designed to support the head end of the internal frame 12. Thus, the posts have horizontal bolts 25 at the top forming pivots for the upper ends of a pair of vertical arms 26; and the frame 12 has rearward bolts 12b receiving the lower ends of the arms 26.

It is now apparent that the head-end of the frame 12 is suspended from the bed posts 11a and may be swung from side to side. Power means to do this are shown in the form of an electric motor 27, a worm-gear drive 28, and a link 29 from the latter to one of the bolts 12b; and the lateral swing of the frame 12 is pivotal about the ball-joint 21—12a. Moreover, this movement will be most prominent in the region of the head-end of the bed where the need for imparting relaxation and sleep to the bed occupant is greatest. Since no reciprocating movement is needed at the foot end of the bed, beds having a low board or no board at such end can be adapted for the desired movement by means of the simple ball-joint 21—12a at the foot end; and the transverse brace 18 adds lateral support for the frame to keep it level. Further, the power source for operating the frame is compactly assembled under the head end of the bed. A guard 30 is shown erected at the head end of the frame 12 to check bed-clothes from reaching the zone of the frame-operating mechanism. Finally, a time clock 31 may be provided at the head of the bed as shown in FIGS. 1 and 3 to shut the motor 27 off after a prescribed operating period. When the link 29 is reciprocated as a "pitman drive," and through the connection of links 26 at 12b and 25, the head of the bed passes in a gentle arc (equal to the "throw" of the "pitman drive" through the normal horizontal plane in which the head of the inner frame 12 is returned and suspended. At the same time, the foot of the bed, through the connection of brace 18, arms 18a, bolts 20, screw 15, 15a and ball and socket 21, 21a, is substantially restrained to pivotal movement in a horizontal plane, due to any resultant forces transmitted through side members of inner frame 12 due to torque imposed on inner frame 12 (at the head) when oscillatory movement is applied through "pitman drive" 29, disc 28 and motor 27.

I claim:

1. A bedstead, comprising in combination:
 a generally horizontal base having a foot and head integral with a headboard;
 an inner support frame;
 first support means displaceably suspending said inner support frame adjacent said headboard for oscillatory movement in an arc passing slightly through a generally horizontal plane in a path above said horizontal base;
 second support means pivotally supporting the inner frame from beneath and adjacent the foot of said horizontal base for oscillatory movement about a vertical pivot,
 said second support means including an element substantially restraining the pivotal movement of said foot to a substantially horizontal plane.
2. The structure as claimed in claim 1 including power means on said horizontal base and including a periodically

oscillatable force transmitting portion operatively connected to said inner support frame.

3. The structure as claimed in claim 1 in which said first support means comprises elongated links terminally journaled on horizontal axes between the headboard and said inner support frame.

4. The structure as claimed in claim 3 including power means on said horizontal base and including a worm-gear drive having an eccentrically-pivoted link connected to a rotary disc, said last mentioned link being pivotally connected at the terminal pivot of one of said first mentioned links at the inner support.

5. The structure as claimed in claim 1 in which said second support means comprises a vertical center post anchored to said horizontal base centrally and adjacent

the foot thereof, said center post including an upper anti-friction ball, said inner support frame including a socket complementary to said ball and journaled thereon, a brace journaled on said center post adjacent said horizontal frame, said brace including diverging arms terminally connected to transversely spaced, undersurface portions of said inner support frame.
